A. B. Upsham,
Attorney.

UNITED STATES PATENT OFFICE.

ROBERT P. BARNSTEAD, OF BOSTON, MASSACHUSETTS.

ELECTRIC HEATER.

1,360,999.

Specification of Letters Patent.

Patented Dec. 7, 1920.

Application filed October 29, 1919. Serial No. 334,265.

To all whom it may concern:

Be it known that I, ROBERT P. BARNSTEAD, of Boston, in the county of Suffolk and Commonwealth of Massachusetts, have 5 invented certain new and useful Improvements in Electric Heaters, of which the following is a full, clear, and exact specification.

One of the difficulties found to exist in 10 connection with electric water heaters is that which results in case the attendants omit to keep the same supplied with water. The water having all boiled away, with the heater still in action, the receptacle is liable to become overheated and also the solder uniting 15 the heater units thereto, and the entire apparatus injured and made useless, either permanently or until repairs can be made.

The object of this invention is the effect- 20 ing of means whereby a degree of heat somewhat in excess of that of boiling water but less than what will be injurious to the parts, can be made to break the electric circuit to the heater units and thereby guard 25 against injury.

To this end I prefer to form one of the electric terminals with a fusible section such that when the excessive heat reaches it, the parts will separate and break the circuit.

30 In the drawings forming part of this specification, Figure 1 is a sectional elevation of a water receptacle having a single heater unit therein, and with the terminals of the heater unit provided with my im- 35 proved circuit-breaking device. Fig. 2 is a side view of the fusibly separable terminal. Fig. 3 is a sectional view of the same. Fig. 4 is a view of parts thereof separated. Fig. 5 is an end view showing the manner in 40 which a spring device acts to insure separation of the parts after the fusible portion has melted. Fig. 6 is a side view of the same.

In Fig. 1, the water receptacle 1 is shown 45 having a single heater unit 2 therein of well known form, and rising from the bottom of the receptacle. Depending from the lower end of the heater unit are its two terminals 3 and 4 designed to plug into 50 a hand-piece 5 of well known construction joined by a cable 6 to a source of current. The terminal 4 may be of usual construction, but the terminal 3 is the one embodying the main feature of my invention.

55 As shown in Figs. 2 and 3, the terminal

section 7 which communicates directly with the interior of the heater unit, is provided with a threaded head 9, preferably formed with a shoulder 10, upon which threaded head is screwed the internally threaded 60 thimble 11 having a flat outer end 12. The terminal 3 is also formed with a flat end 13 somewhat enlarged diametrically, and between these two flat surfaces is placed a wafer of easily fusible metal 14 suitably 65 soldered or fused to both. While I have illustrated this fusible metal as though it were nearly an eighth of an inch thick, it is hardly necessary to have it quite so thick, especially when my spring separator is used. 70

This spring separator consists of a leaf 75 spring 15 attached to the hand piece 5 near the socket which receives the terminal 3, and gives an inward bend past the oppo- 80 site margin of the terminal, as shown in Fig. 6. Normally this spring rests against the thimble 11 and does not affect the opera- 85 tion of the heater in any way so long as the fusible metal holds the parts together. But the instant any excessive heat melts the 86 wafer 14 or otherwise causes it to release its hold upon either or both the flat surfaces 12, 13, then the spring 15 immediately acts to turn the hand piece 5 on the terminal 4 as an axis until the terminal 3 is out of 85 alinement with the thimble 11 and free of 90 possible contact therewith.

When it is found that the water recep- 95 tacle is empty and the current cut out from its heater unit, it is the work of a moment 90 only to unscrew the thimble 11, after pulling off the hand piece 5, and to screw on a fresh thimble and attached terminal. The re- 100 application of the hand piece again switches on the current, and the water which may now be poured into the receptacle is soon set to heating.

If both terminals were made like the 105 fusible one above described, the spring 15 would be unnecessary, since the hand piece would simply drop away from the heater; but I prefer to have one alone thus made fusible for the purpose of halving the delay and expense of making the change after an overheating has occurred.

I find that by giving a twist to the cable 6 previous to the application of the hand piece 5 to the terminals, this twist will serve to turn the terminal 3 away from possible 110 contact with its thimble 11, without the em-

ployment of the spring 15, but I prefer to provide this spring because so many attendants will forget to thus twist the cable.

What I claim is:

- 5 1. An electric terminal comprising a terminal member having a flat end, a member having a flat end easily detachable from the circuit, and a thin wafer of easily fusible metal uniting said flat ends.
- 10 2. The combination with a heater unit having terminals one of which is formed with a threaded head, an internally threaded thimble screwed upon said head, a terminal member, and a body of easily fusible metal uniting the latter to said thimble.
- 15 3. The combination with a heater unit having terminals one of which is in sections, easily fusible metal uniting said sections, and a hand piece having a cable connected

therewith, the hand piece being adapted for engagement with both terminals, said hand piece being adapted to revolve on one of the terminals when the easily fusible metal of the other has melted.

4. The combination with a heater unit 25 having terminals one of which is in sections, easily fusible metal uniting said sections, a hand piece having a cable connected therewith and adapted for engagement with both terminals, and a leaf spring attached to 30 said hand piece and curved to rest against the separable section and turn the sections out of possible contact with each other when the fusible metal melts.

In testimony that I claim the foregoing 35 invention, I have hereunto set my hand this 27th day of October, 1919.

ROBERT P. BARNSTEAD.
